UNITED STATES PATENT OFFICE.

NELSON S. BURTON, OF ARDMORE, OKLAHOMA.

ROTARY WELL DRILL.

Application filed February 19, 1925. Serial No. 10,224.

To all whom it may concern:

Be it known that I, NELSON S. BURTON, citizen of the United States, residing at Ardmore, in the county of Carter and State 5 of Oklahoma, have invented certain new and useful Improvements in Rotary Well Drills, of which the following is a specification.

This invention relates to rotary well-drilling apparatus and more particularly to that 10 type of drilling apparatus in which a drill of less size than the bore desired is employed, and the drill pipe has arranged thereon, above the drill-bit, a reamer for enlarging the bore. This type of drilling 15 apparatus is employed in difficult formations for the reason that it is particularly adapted for the production of straight bores therein.

An important object of the invention, in 20 the form thereof embodying a set of removable reamer-blades, is to provide an improved mounting for such blades; and to provide a bit-carrying pipe-member having a threaded pin engaging a threaded recess 25 interiorly of the reamer-body, at a point about midway of the length thereof.

Another object is to provide a modified construction wherein the bit-carrying pipe-member and the reamer-body carrying the 30 removable reamer-blades are integral, thus simplifying the construction.

Other objects will appear as the specification proceeds and the nature of the invention is more fully disclosed.

The invention, in its various forms, is disclosed in the accompanying drawings. The different views thereof may be briefly described as follows:

Figure 1 is a view, in side elevation, of 40 the drilling assembly constructed in accordance with one form of my invention;

Figure 2 is a view in central longitudinal section thereof;

Figure 3 is a top plan view thereof;

Figure 4 is a cross section taken on the plane of the section line 4-4, Fig. 1;

Figure 5 is a view in side elevation, showing a slightly modified form of construction;

Figure 6 is a central longitudinal section 50 through the form shown in Fig. 5;

Figure 7 is a fragmentary central longitudinal sectional view of a still further modified form.

Referring, now, in detail to the drawings and, first, to Figs. 1 to 4 thereof:

1 indicates a reamer-body, which is, in this instance, tubular, providing the bore 2 therethrough, and is exteriorly formed with a number of longitudinally extending 60 grooves 3 (two thereof being shown in the drawings), which may be of tapering contour longitudinally, as shown in Fig. 1, for the reception of the similarly tapering portions 4, 4 of the shanks of reamer-blades 65 5, 5, said tapering portions having shoulders 5^a, 5^a seating under the lower ends of the reamer-body 1, as shown in Figs. 1 and 2.

The reamer-body 1 is provided, at its upper end, with a tapering, threaded pin or 70 nipple 6 for engagement with the lower end of a line of drill-pipe. At its other end, the reamer-body is hollowed out longitudinally, providing a longitudinally-extending chamber 7 having, at its upper end, the threaded 75 socket 8, to be engaged by the upper threaded end 9 of a pipe-member 10 adapted to carry a fish-tail drill-bit 11. As shown, the socket 8 is disposed interiorly of the reamer-body 1, preferably at a point mid- 80 way of the length thereof.

The reamer-body 1 is provided, adjacent the grooves 3, with two pairs of notches 12, the notches of each pair being oppositely disposed, as shown in Figs. 1 and 4, and 85 which notches receive the heads 13 and nuts 14 of bolts 15, which pass through the inner end walls of said notches and transversely through the tapering portions 4 of the shanks of the reamer-blades 5. By the means just described, the reamer-blades are secured to reamer-body and held against accidental displacement. Additional means are, however, provided for securing said reamer-blades 90 removably in position, and these supplemental securing means are advantageous in case the nuts 14 work loose and fall off the bolts 15, thus permitting the latter to fall out. The supplemental securing means will now be described. When in operative position, the upper ends of the tapering portions 4 of the shanks of the reamer-blades 95 100

5, 5 project somewhat above the annular shoulder 16 toward the upper end of the reamer-body, and these projecting extremities of said tapering portions of the shanks 5 of the reamer-blades are provided with oppositely disposed notches 17, 17, to receive the inner ends of latches 18, 18, which are slid into operative position in guiding grooves 19 in said shoulder 16. Screws 20 10 secure the latches in their operative position of engagement with the notches 17 of the shanks of the reamer-blades.

The drilling-device shown in Figs. 5 and 6 is substantially similar to that of the preceding figures, the principal difference being that the bit-carrying pipe-member 10^a and the reamer-body 1^a are integral, and this construction is advantageous from the standpoint of simplicity of construction. As in 20 the construction shown in Figs. 1 to 4, the reamer-blades 5^a, 5^a are removable, and constructed similarly to those shown in Figs. 1 to 4, and are similarly held in position.

In the form of device shown in Fig. 7, the 25 bit-carrying pipe-member 10^b is integral with the lower end of the drill-pipe 21, the latter, at its point of union with the former, being provided with the threaded pin, of lesser diameter than the drill-pipe 21, so as 30 to form at the inner end of said pin a shoulder 23, against which seats a washer or collar 24 provided with radial ports 25, 25 communicating with radial ports 26, 26 in the drill-pipe 21, the latter ports communicating, in turn, with the bore, or longitudinally-extending central port, 27 of the drill-pipe 21 and bit-carrying pipe-member 10^b. Branch ports 28, 28 in the collar 24 provide 35 communication between the ports 25, 25 and longitudinally-extending ports 29, 29 in the sleeve-member 32 having the internally-threaded upper portion 30 adapted to screw upon the threaded pin 22. The ports 29 40 discharge in front of the reamer-blades (not shown) which are removably carried by the sleeve-member 32 in the manner shown in Fig. 1 (namely, by means of the bolts 15 shown in Fig. 1). The ports described and shown permit water under pressure to pass 45 down through the device and clear the bit and reamers of sediment.

Having thus fully described my invention, what I claim as new and desire to secure by Letters-Patent of the United States is:

55 1. The combination with a reamer-body having an internal, threaded socket at a point midway of the length thereof, a bit-carrying pipe-member having a threaded end engaging said socket, said reamer-body being provided exteriorly with longitudinally-extending grooves, reamer-blades having shanks disposed in said grooves, and means for holding said shanks in said grooves against accidental displacement.

60 2. The combination with a reamer-body

having an internal, threaded socket at a point midway of the length thereof, a bit-carrying pipe-member having a threaded end engaging said socket, said reamer-body being provided exteriorly with longitudinally-extending, tapering grooves, reamer-blades having shanks provided with tapering portions engaging said grooves, and means for holding said shanks in said grooves against accidental displacement. 70 75

3. The combination with a reamer-body having an internal, threaded socket at a point midway of the length thereof, a bit-carrying pipe-member having a threaded end engaging said socket, said reamer-body being provided exteriorly with longitudinally-extending grooves, reamer-blades having shanks seated in said grooves, and bolts passing through said reamer-body and said shanks for holding the latter against accidental displacement. 80 85

4. The combination with a reamer-body having an internal, threaded socket at a point midway of the length thereof, a bit-carrying pipe-member having a threaded end engaging said socket, said reamer-body being provided exteriorly with longitudinally-extending grooves, reamer-blades having shanks seated in said grooves, said shanks being notched toward their upper ends, and latches slideable upon said reamer-body and engageable with said notches. 90 95

5. The combination with a reamer-body having an internal, threaded socket at a point midway of the length thereof, a bit-carrying pipe-member having a threaded end engaging said socket, said reamer-body being provided exteriorly with longitudinally-extending grooves, reamer-blades having shanks seated in said grooves, said shanks being notched toward their upper ends, latches slideable upon said reamer-body and engageable with said notches, and means for holding said latches in operative position. 100 105

6. The combination with a reamer-body having an internal, threaded socket at a point midway of the length thereof, a bit-carrying pipe-member having a threaded end engaging said socket, said reamer-body being provided exteriorly with longitudinally-extending grooves, reamer-blades having shanks seated in said grooves, bolts passing through said reamer-body and said shanks for holding the latter against accidental displacement, said shanks being notched toward their upper ends, and latches slideable upon said reamer-body and engageable with said notches. 110 115

7. The combination with a reamer-body having an internal, threaded socket at a point midway of the length thereof, said reamer-body being provided exteriorly with longitudinally-extending grooves, reamer-blades having shanks disposed in said grooves, and means for holding said shanks 120 125 130

in said grooves against accidental displacement.

8. The combination with a reamer-body provided externally with longitudinally-extending grooves, of reamer-blades having shanks removably seated in said grooves, said shanks being notched toward their up-

per ends, and latches slideable upon said reamer-body and engageable with said notches.

In testimony whereof, I hereunto affix my signature.

NELSON S. BURTON.
